UNITED STATES PATENT OFFICE.

EDWARD E. JOHNSON, OF ST. PAUL, MINNESOTA.

TUBE-FORMING MACHINE.

1,141,712.

Specification of Letters Patent. Patented June 1, 1915.

Application filed June 4, 1908. Serial No. 436,648.

To all whom it may concern:

Be it known that I, EDWARD E. JOHNSON, of St. Paul, Ramsey county, Minnesota, have invented certain new and useful Improvements in Tube-Forming Machines, of which the following is a specification.

The object of my invention is to provide a machine for forming tubular well screens, an invention which forms the subject matter of Patent No. 899,054.

The invention consists generally in providing means for first milling the strand or wire of which the tube is formed, second punching the necessary holes therein to adapt the tube for use as a well screen, and third, rolling up the wire to form the tube and locking the coils together.

Further, the invention consists in means whereby the parts of the machine are rendered adjustable to adapt them for different speeds and for producing slight variations in the formation of the tubing.

Further, the invention consists in means for making tubing of different sizes.

Further, the invention consists in various constructions and combinations, all as hereinafter described and particularly pointed out in the claims.

In the accompanying drawings, forming part of this specification; Figure 1 is a side elevation of a tube-forming machine embodying my invention. Fig. 2 is a plan view of the same. Fig. 3 is an end view. Fig. 4 is a sectional view on the line $x-x$ of Fig. 1. Fig. 5 is a sectional view on the line $y-y$ of Fig. 1. Fig. 6 is a sectional view on the line $z-z$ of Fig. 5. Fig. 7 is a sectional view through the frame and arbor of the milling mechanism. Fig. 8 is a sectional view on the line $w-w$ of Fig. 7. Fig. 9 is a sectional view on the line $v-v$ of Fig. 7. Fig. 10 is a sectional view on the line $a-a$ of Fig. 7. Fig. 11 is a sectional view on the line $o-o$ of Fig. 4. Fig. 12 is a detail sectional view of the wire punching device.

Fig. 13 is a detail sectional view of one of the guiding and pressure rollers. Fig. 14 is a detail view of a portion of the strand or wire. Fig. 15 is a sectional view of the wire. Fig. 16 is a sectional view of a portion of the tubing illustrating the manner of locking the coils of wire together. Figs. 17 and 18 are detail views of the standard upon which the completed tubing is supported.

In the drawing, 2 represents a suitable base upon which the frame 3 of the machine

is mounted. On the left hand side of the machine a reel having a hank of wire 4 wound thereon, is mounted, the wire being unwound from the reel during the operation of the machine. This reel I have thought it unnecessary to illustrate as it forms no part of my present invention. The wire is obtained from wire-drawing mills formed in cross section substantially as shown in Fig. 15, except that the right hand groove is not drawn therein but is formed by a saw, and the first step in the operation of the machine is to form a groove in the wire, of the required depth and one that will be uniform throughout the length of the wire. To accomplish this I provide adjustable guide rollers 5 and 6 between which the wire is inserted. A saw arbor 7 is journaled in a bracket 8 and is provided with a driving pulley 9. This pulley is driven independently of the other mechanism of the machine from a belt 10 to enable the operator to start the saw and speed it up to the desired point before setting the rest of the mechanism in motion. This enables me to stop the machine and start it again without affecting the milling operation. The arbor 7 has a device for end adjustment, consisting preferably of a threaded thrust collar 11 and a loose thrust ring 12 which tends to reduce the wear. A collet 13 is pinned on the arbor and has a recess in one end to receive the projecting end of the box 14 of said arbor. The collet at its opposite end has a broad flat face 15 between which and a corresponding face 16 on a collet 17 the saw 18 is gripped and held. The faces of these collets are made as large as possible to support the saw close to the work, for as the groove is cut deeper on one side than on the other the saw would tend to bind, unless supported laterally.

19 is a guide having a longitudinal groove 20 in its under side arranged to contact with 100 and support the wire on the top, bottom and inner edge.

Guide blocks 21 are provided having holes 22 to receive pins 23, said holes being of sufficient size to permit lateral adjustment 10 of said blocks by means of adjusting screws 24 mounted in the housing 25. These guide blocks support the outer edge of the wire and are held in close contact therewith by the adjusting screws. The guide 19 has an 110 inclined rear face 26 and a wedge 27 is adapted to fit between said face and the

wall of the housing 25 and has a threaded end secured by a sleeve nut in an arm 28. By adjusting the sleeve nut the wedge may be moved lengthwise to release or clamp 5 the guide. The guide is held against the wedge by means of adjusting screws 29. Transverse bars 30 fitting within recesses in the housing and the top of the guide lock the latter against lengthwise movement. By 10 means of this wedge and the adjusting screws, the guide may be moved in or out to adjust the wire laterally with respect to the saw and by means of the guide blocks 21 the tension of the wire as it is drawn 15 through the guide can be regulated.

The position of the guide is varied vertically with respect to the saw arbor to accommodate it to saws of different diameter and to regulate the cut of the saw in making 20 tubing of different sizes. This I accomplish by making the housing 25 vertically slideable on the bracket 8 in which the saw arbor is mounted. The housing and bracket are tongued and grooved together and are held by a bolt 31 passing through holes of 25 sufficient size in the housing to allow vertical adjustment by means of adjusting screws 32. The outer collet 17 has an extension that is feathered on the arbor 7 and a collar 33 has an outwardly projecting lip 34 at its inner end and is threaded on the extension of the collet 17 so that endwise adjustment of the collar 33 is permitted, the collet 17 being locked against rotary adjustment 30 by its feathered connection with the arbor. A milling cutter 35 has an inwardly projecting lip 36 interlocking with the lip on the inner end of the collar 33 and a pin 37 is mounted in said collar and is arranged 35 to project into a groove 38 in a cap 39, and in the end of the latter, whereby the cap is locked against rotary movement, and the collar is also prevented from turning except with the cap 39. This cap fits loosely on the 40 collar and the outer end of the arbor is threaded and provided with a lock nut 40 which bears on the said cap and normally locks it against endwise movement. The 45 milling cutter is provided with a series of teeth 41.

From the foregoing, it is evident that if the arbor 7 is held against rotation and the lock nut 40 is loosened, the cutter 35, the collar 33 and the cap 39 may be revolved as 50 one piece and the threaded connection between the collar 33 and the collet 17 will cause endwise movement of the milling tool and adjust it with reference to the edge of the wire. When the lock nut 40 is tightened 55 the collet 17 will be forced against the saw, and through friction between the threads of the collet 17 and the collar 33 will lock the milling tool in position and against rotation with respect to the saw. 60 The milling tool will also be forced against

the lip at the inner end of the collar 33 and be locked against endwise movement with respect to the arbor. I am thus able, by means of one lock nut to hold the saw and the milling tool in any desired relative position. It is important to do this as I am thus able to regulate the amount cut off the edge of the wire by the cutter and determine the proper width of the groove formed between the coils of wire in the 75 completed tube. The width of this groove will vary with different conditions and may be made according to the needs of each particular case.

The housing incloses the outer portion of 80 the arbor and extends back to the outer journal and permits the free discharge of the cuttings of the saw and the milling tool, and for the purpose of keeping the cutters cool and clean I provide a nozzle 41' 85 arranged to direct a fluid through the wall of the housing upon the cutting tool. The recessed end of the collet 17 inclosing the box 14 prevents any of the tool cuttings and liquid from working into the bearings. The 90 cap 39 has a lip 42 formed thereon between which and the end of the milling tool an annular recess 43 is formed to collect the liquid from the tool and throw it off by centrifugal force within the housing. The 95 opening in the wall of the housing through which the cap 39 extends must necessarily be of sufficient size to allow vertical adjustment of the housing. Consequently the lip and recess are necessary to prevent the liquid 100 from flowing out on the cap and being thrown off therefrom upon the floor and other parts of the machine. A discharge opening 44 for the tool cuttings is provided, beneath which suitable receptacles 105 (not shown) may be arranged to receive the cuttings and return the liquid to the pump to be used over again.

The punching head.—The operation of forming the tube should be continuous. The 110 wire should, therefore, be delivered to the rolling mechanism continuously and suitable punching mechanism is provided which will form holes a fixed distance apart in the uniformly moving wire or strip of metal. A 11 driving shaft 45 is journaled in the frame 3 and has a fly wheel pulley 46 on one end. A pinion 48 on the shaft 45 meshes with an idle gear 49 which in turn drives a pinion 50 on a shaft 51. A stud 52 is mounted in the 12 frame 3 above the shaft 45 and is provided with an eccentric bushing 53 having a flanged outer end. The punch body 54 is pivoted on said bushing. Within this punch body is a reciprocating plunger 55 connected by the rod 56 with a crank pin 57 on the end of the shaft 45. As the wire is constantly in motion during the punching operation it is necessary that the punch body have an oscillating movement to permit the punch to 1

travel with the wire. I therefore connect the punch body with a crank pin 58 on the shaft 51 through a pin 59 and connecting rod 60. The shaft 51 revolves at the same speed as the shaft 45 and consequently the oscillations of the punch body will be properly timed with respect to the reciprocation of the punch plunger. The wire moves at a constant speed and the punch body should therefore move at the same rate and in the same direction. Various mechanical devices might be employed for producing this result but I have found that the simple connection of the punch body with the shaft 51 will answer the purpose and be easy of maintenance. The punch plunger 55 is provided with a socket at its lower end to receive a hardened steel sleeve 59 which is bored to fit the punch 59'. The punch is preferably made of steel wire with a small head formed on its upper end. The sleeve supports the punch throughout its length and permits it to be made of material that is always at hand and readily replaced when worn or broken. A suitable set screw 59" secures the sleeve 59 in its socket. The die block 60' is fitted into the lower end of the punch body and is held in place by a following plate 61 and screws 62. A die 61' is fitted into the block 60' and is held in place therein by a stripper plate 61" and screws 62'. The stripper plate has a vertical opening 63' therethrough for the passage of the punch, and a horizontal opening 63" to receive the moving wire and guide it during the punching operation and strip it from the punch when the hole has been formed.

The crank pin 57 has an eccentric bushing 63 on which the connecting rod 56 is supported, said bushing having a flanged outer end provided with a series of notches 64 adapted to receive a pin 65 by means of which the bushing is locked against accidental rotary movement. Upon loosening the bushing and rotating it the stroke of the plunger and punch may be regulated. By means of the eccentric bushing 53 the swinging punch body may be vertically adjusted to raise or lower the die block. This bushing when adjusted is locked by means of the nut 53' on the threaded end of the stud 52.

The tube-rolling mechanism.—A standard 66 is mounted on the base of the machine 55 and has a horn 67 formed thereon adapted to enter an opening in a disk 68 that is bolted to a flange 69 on said standard. A disk 70 is formed integrally with the disk 68 and has a stud 69' on which the lower mandrel 70' of the tube rolling mechanism is mounted. The inner end of this lower mandrel has a gear 71 whose pitch line coincides with the outer diameter of the tube to be rolled. An upper mandrel 72 is mounted on a shaft 73 and a gear 74 on said shaft meshes with the gear 71 and drives the lower mandrel. The main driving shaft is geared to the shaft 73 through gear wheel 49, large gear 75, pinion 76 and gear 77. The tube-rolling mandrel thus operates continuously 79 with the main driving shaft.

The upper mandrel 72 is provided with an annular rib 78 that is adapted to enter the groove formed in the wire and guide it as it is rolled around the lower mandrel. 75 The upper mandrel is capable of vertical adjustment to regulate the space between it and the lower mandrel by means of an eccentric bushing 79 which incloses the shaft 73 and is provided with an arm 80 having 80 an adjustable connection 81 with a curved rod 82. Upon loosening this connection the operator may move the arm up or down to rotate the eccentric bushing and raise or lower the upper mandrel for the purpose 85 of relieving the pressure on the wire or increasing it. A series of guide rollers 83 are mounted on studs 84 in the disk 70. These rollers are driven by gears 85 on said studs meshing with the gear 71 on the inner end 90 of the lower mandrel. The guide rollers 83 are provided with annular ribs 86 which are adapted to enter the groove in the wire, and the guide rollers are so arranged that these ribs are in different vertical planes, as indicated in Fig. 2, so that they will conform to the spiral or helical coil of the wire composing the tube. In other words the pitch of the ribs directs the wire under the top mandrel with the desired inclination to the axis of the tube. Preferably there are six coils to the inch. The guide rollers are arranged as near together as practicable and serve to hold the wire down firmly on the lower mandrel, thus keeping it true to the 100 circle of the mandrel.

The roll 87 on the left hand side of the upper mandrel is located above the wire as it enters the tube-forming head and consists of a plain cylindrical roll bearing on the 110 surface of the completed tubing. It has no gear connection with the lower mandrel and no function in guiding the spiral. The mandrels operate together and the lower mandrel with the tubing thereon has the same 115 ratio of velocity in its revolution as the upper mandrel. The disk 68 is secured by bolts 88 to the flange 69, and whenever desired the mandrels may be removed from the machine and others substituted therefor. The wire 4 120 has the groove 89 formed therein when drawn. The groove 90 is cut by the saw. The edge 91 of the wire is trimmed to the required depth by the revolving milling tool and on the opposite edge of the wire a lip 92 125 is formed which enters the groove 90 during the formation of the tubing. A lip 93 is provided on the wire between the grooves 89 and 90 and when the coils are wrapped around the tube-forming head, the lip 92 of 130

each coil will be pressed into the groove 90 of the contiguous coil by the pressure of the mandrels, and the lip 93 will be rolled or spun over the interlocking coils by the pressure of the mandrels until it is flush with the inner surfaces of the coils as indicated in Fig. 16, and a smooth even surface is formed for the interior of the tubing. The holes 94 punched in the bottom of the groove 89 by the punching mechanism are exposed by the trimming of the edges 91 as they pass through the milling tool. The degree of exposure of these holes will depend of course, upon the amount trimmed off the edge of the wire by the action of the milling tool. If only a very light mill is trimmed off then a narrow slot only will be formed, extending spirally around the tubing between the separate coils, but if a considerable portion of the edge 91 is removed then the full width of the holes will be visible and the opposition to the passage of liquid and sand through the walls of the tubing considerably reduced.

I propose to vary the cutting of the milling tool and the width of the spiral slot in the walls of the tubing according to the requirements and the conditions surrounding each particular installation. The pressure of the mandrels on the wire will be sufficient to feed it, and the necessary tension to keep the wire taut and prevent vibration can be easily obtained by means of the adjustable guide blocks on the milling head.

The tube-forming head is removable from its support and by substituting another of different size I am able to vary the diameter of the tube formed.

If desired a solid tube may be formed by coiling the wire in the manner described and omitting the edge-trimming or milling operation and the punching of the holes in the bottom of the groove. The wire will then pass from the saw directly to the tube-forming head where the spirals or coils will be lapped one upon another and locked together. By means of the arm 80 and its connections the operator can raise or lower the upper mandrel and regulate the pressure on the wire according to the degree required for the proper locking together of the spiral coils.

In Figs. 17 and 18 I have shown a standard adapted for supporting the completed tubing. This standard consists of a base 105 having points 106 on its lower surface to prevent it from slipping, and provided with a centrally arranged socket to receive a vertically adjustable shank 107 secured to said socket by means of a set screw 108. Arms 109 are carried by the shank and provided with anti-friction rollers 110, between which the tubing is supported. The lower ends of the arms have weights 111 thereon.

I claim as my invention:

1. The combination with means for forming a groove in a wire, of means for continuously feeding said wire thereto, of means for punching a series of holes successively through said wire as it is delivered from 70 said groove forming means.

2. The combination with means for forming a longitudinal groove in a flattened wire, of means for continuously feeding said wire thereto, means for trimming the edge of 75 said wire and means for punching holes successively through said wire as it is delivered from said groove forming means.

3. The combination with a supporting frame, of a punching head mounted thereon, 80 means for laterally oscillating said head, means for continuously feeding a wire through said head, means for punching holes successively in said wire as it is fed through said head and means subsequently operating 85 upon said wire for forming a flat surface thereon.

4. The combination with a supporting frame, of an oscillating punching head mounted thereon, means for adjusting said 90 head vertically, means for laterally oscillating said head, means for continuously feeding the wire through said head, and means for punching a series of holes successively in the wire as it is fed through said head. 95

5. The combination with a supporting frame, of a stud mounted thereon, an eccentric bushing carried by said stud, a punching head journaled on said bushing, means for feeding a wire through said head, means for punching a series of holes successively in said wire, as it is fed through said head, and means for oscillating said head about said eccentric bushing, and in the direction longitudinally of said wire. 100

6. The combination of a supporting frame, of a punching head mounted thereon, means for feeding a wire continuously through said head, means for oscillating said head in a direction longitudinally of 110 said wire, a die mounted in said head, means for adjusting said die vertically, a reciprocating punch arranged to punch a series of holes successively in said wire as it is fed through said head and means subsequently 115 operating upon said wire for forming a flat surface thereon.

7. The combination with a supporting frame, of a punching head pivoted at its upper end thereon, means for feeding a wire 120 through said punching head, means connected to the lower end of said head for oscillating the same in a direction longitudinally of said wire, a punching die in said head through which the wire is fed, and means carried by said punching head for punching a series of holes in said wire as the same is fed through said head. 125

8. The combination with a supporting frame, of a punching head pivoted thereto, means for adjusting said head vertically, a driving shaft, a punching plunger slidably mounted in said head, and having adjustable connection with said shaft whereby the working position of the plunger may be varied, a punch carried by said plunger, a die mounted in said head, means for continuously feeding the wire between said punch and said die, and means for oscillating said head in a direction longitudinally of said wire.
9. The combination with a supporting frame, of a punching head pivoted thereto, means for adjusting said head vertically, a plunger slidably mounted in said head, a driving shaft having a crank pin connection with said plunger, an eccentric bushing, and means coöperating therewith whereby said plunger may be raised or lowered, a punch mounted in said plunger, a die carried by said head and coöperating with said punch, means for feeding the wire continuously between said punch and said die, and means for oscillating said head in a direction longitudinally of said wire.
10. A machine for forming tubes including in combination, means for forming a groove in a wire, an upper and a lower mandrel, means for revolving said mandrels, said upper mandrel having a rib formed thereon for engaging a groove in the wire forming the tube, and guiding the same, and wire guiding rolls provided at intervals around the periphery of said lower mandrel, each of said rolls having a rib for engaging the groove in said wire and guiding the same, said guiding rolls being disposed so as to direct said wire spirally about said lower mandrel.
11. A machine for forming tubes including in combination, an upper and a lower mandrel, means for revolving said mandrels, said upper mandrel having a rib formed thereon for engaging a groove in the wire forming the tube and guiding the same, and wire guiding rolls provided at intervals around the periphery of said lower mandrel, each of said rolls having a rib for engaging the groove in said wire, and guiding the same, said guiding rolls being disposed so as to direct said wire spirally about said lower mandrel, and means for adjusting the upper mandrel relative to the lower mandrel.
12. A machine for forming tubes including in combination, an upper and a lower mandrel, means for revolving said mandrels, said upper mandrel having a rib formed thereon for engaging a groove in the wire forming the tube and guiding the same, wire guiding rolls provided at intervals around the periphery of said lower mandrel, each of said rolls having a rib for engaging the groove in said wire and guiding the same, said guiding rolls being disposed so as to direct said wire spirally about said lower mandrel, and an eccentric bushing for adjusting the position of the upper mandrel relative to said lower mandrel.
13. A tube forming machine including in combination, means for milling a groove in a wire, means for punching holes successively in said wire, and a tube forming head including an upper and a lower mandrel, said upper mandrel having a rib formed thereon for engaging the groove in the wire for guiding the same, guiding rolls arranged at intervals about said lower mandrel and having ribs formed thereon for engaging the groove in said wire and guiding the same, said guiding rolls being arranged whereby said wire is guided in a spiral direction about said mandrel.
14. A tube forming machine including in combination, means for guiding a wire having a groove formed in its upper face and a downwardly projecting lip on its lower face, means for engaging and grooving the lower face of said wire, a mandrel about which said wire may be wound, a second mandrel coöperating with said first named mandrel for guiding said wire about said first named mandrel in a spiral direction, and for turning said lip so as to lock the flat wire in one spiral with the adjacent edge of said wire in the next spiral, guiding rolls arranged about said lower mandrel for guiding and directing said wire about said lower mandrel in a spiral direction.

In witness whereof, I have hereunto set my hand this 1st day of June 1908.

EDWARD E. JOHNSON.
